UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING COMPANY, A CORPORATION OF MASSACHUSETTS.

ELECTRIC SWITCH.

Application filed March 22, 1921. Serial No. 454,427.

To all whom it may concern:

Be it known that I, GEORGE A. BURNHAM, a citizen of the United States, residing at Saugus, in the county of Essex and State of Massachusetts, have invented an Improvement in Electric Switches, of which the following is a specification.

This invention relates to electric switches of the type having an inner oil receptacle and 10 an outer spill receptacle, as set forth in my Patent No. 1,413,156, dated April 18, 1922.

In an electric switch of the type above set forth oil may be expelled from the inner receptacle under sufficiently severe circuit-interrupting conditions and collect in the outer 15 or spill receptacle; and the oil level will be lowered in the inner receptacle and raised in the outer receptacle.

An object of this invention is to return oil 20 to the inner receptacle from the outer receptacle subsequent circuit interruption and restore the oil level therein to the normal level whereby the switch may be at all times in a state of maximum circuit-interrupting effectiveness.

The switch embodying the invention may be provided with communicating passages extending between the outer and inner receptacles below the oil level therein and preferably at the lower portions of said receptacles arranged to admit a flow of oil from 30 said outer into said inner receptacle when the oil level in the outer is higher than in the inner receptacle, thereby to replenish oil expelled from said inner into said outer receptacle upon circuit interruption, and restrict the flow of oil from said inner to said outer receptacle through said passages due to a momentarily elevated pressure in said inner receptacle during the period of circuit interruption.

A further object is generally to improve the construction and operation of an electric switch.

45 Certain features of this invention are disclosed in my co-pending application Serial No. 390,850, filed June 22, 1920.

Fig. 1 is a side elevation of an electric switch embodying the invention.

50 Fig. 2 is a plan view of the switch of Fig. 1.

Fig. 3 is a transverse vertical section of the switch.

55 Fig. 4 is a detail illustrating the front view of a valve member.

Fig. 5 is an enlarged sectional detail along line 3—3 of Fig. 1 illustrating the opening through the wall of the inner receptacle and the valve member controlling said opening.

Fig. 6 is a detail similar to Fig. 5 illustrating the valve open with a higher level of oil in the outer than in the inner receptacle thereby to admit a flow of oil from said outer into said inner receptacle.

Fig. 7 is a transverse sectional elevation of 65 the inner and outer receptacles with a modified form of oil communicating passages therebetween.

Fig. 8 is an enlarged detail illustrating 70 the oil passages of Fig. 7.

As here shown, the switch embodying the invention includes the switch frame 10 having the inner oil receptacle 11 and the outer spill receptacle 12 enclosing said inner receptacle disposed beneath said frame, which forms a cover for the receptacles, and supported in position on the grids 13 secured to the rods 14 which are yieldingly supported on the springs 15 carried in recesses in lugs 16 of the switch frame. Stationary switch 80 members 17 and a movable switch member 18 are carried by said frame and depend into the oil contained in said inner receptacle.

Said frame is formed with the inner depending flange or apron 19 which surrounds and is peripherally spaced from the upper portion of the side wall thereof to provide a passage *a* over the top of said inner receptacle down the side wall thereof into the outer receptacle; and said rods 14 may be 85 provided with stop members 20 which serve to hold the inner receptacle spaced below the inner face of the switch frame thereby to form a permanent gas vent passage over the top of the inner receptacle. Said apron extends downward over the outer face of the side walls of said inner receptacle a substantial distance whereby to support the side walls and guide the gas and oil expelled from the inner receptacle into the outer receptacle at a substantial distance below the top thereof.

Said outer receptacle is spaced from said inner receptacle to provide an annular chamber *b* in which to receive the gas and oil and oil vapor expelled from the inner receptacle and collect the oil.

Said switch frame is also formed with a second and outer depending flange or apron 21 which extends downwardly over and is 110

closely spaced from the upper portion of the side walls of said outer receptacle; and gas expelled from the inner receptacle finally passes over the top of the outer receptacle through the passage *c* between said outer receptacle and apron into the atmosphere in a downward direction. While the inner oil receptacle may be held against the inner face of the switch frame by the springs 15, the top of the outer receptacle is preferably spaced below said switch frame to provide a passage therebetween; and there may be a passage over the top of the inner oil receptacle while in contact with the switch frame by reason of irregularities in the lower face of the switch frame. For some purposes the outer flange 21 may be omitted, however.

The lower portion of the side wall of the inner receptacle 11 may be formed with apertures 22 therein to provide oil communicating passages between the outer and inner receptacles; and the wall at the edge of the apertures may be inturned to form a seat 23 for a check valve as in Figs. 3 and 5. Each of said apertures is adapted to be closed during circuit interruption by a valve 24 disposed within the inner receptacle and pivotally suspended from a pin 25 carried by the bracket 26 secured to the side wall of the receptacle above the aperture. Preferably, the pin recess 24^a in said valve is somewhat larger than the pin 25, whereby to facilitate the seating of the valve. Said valves function as check valves to admit a flow of oil from the outer into the inner receptacle when the oil level in the outer is higher than in said inner receptacle but prevent a flow of oil from said inner to said outer receptacle. It is not essential that said valves be strictly oil tight as a slight leakage of oil therethrough from the inner to the outer receptacle is not harmful.

Normally the level of oil in both receptacles is adapted to stand at the same level, as at *d*, Fig. 3, and preferably at a substantial distance below the top of the receptacles whereby to provide a relatively great expansion space *e* above the oil in the inner receptacle as contrasted with the usual type of switch, whereby the current interrupting capacity of the switch may be enhanced, and to provide a relatively deep expansion chamber *f* above the oil in said outer receptacle in which to condense oil vapor and collect oil discharged therein from said inner receptacle without the discharge of substantial quantities of oil from the outer receptacle into the atmosphere. Said valves 24 may normally be closed or they may be open.

Upon circuit interruption, conditions within the inner receptacle may be such as to increase the pressure therein and cause the expulsion of gas and oil vapor and liquid oil into the outer receptacle. The gas will

finally escape from the outer receptacle to the atmosphere while the greater part of the oil vapor will condense and, with the liquid oil, collect in the outer receptacle and raise the oil level therein above that in the inner receptacle; and the oil level in the inner receptacle will be lowered by reason of loss of oil therefrom. During the period of elevated pressure in the inner receptacle the valves 24 will be forced and held against their seats thereby to prevent an appreciable flow of oil from the inner to the outer receptacle. When the pressure within the inner receptacle is reduced substantially to atmospheric the higher head of oil in the outer receptacle will operate to force said valves 24 open and permit a flow of oil from the outer into the inner receptacle until a quantity of oil equivalent to that expelled from the inner to the outer receptacle has been delivered or restored to the inner receptacle and the level of oil in both receptacles is again at substantially the same level. In this manner oil expelled from the inner oil receptacle under conditions resulting from circuit interruption will be automatically restored to the inner receptacle and consequently the necessity for frequent replenishing of oil manually to the inner receptacle is obviated.

It is not essential that the communicating passages between the outer and inner receptacles be closed by valves during circuit interruption. In Figs. 7 and 8, a construction is illustrated wherein valves are unnecessary. As shown in these figures the communicating passages 22^a in the side wall of the inner receptacle are of relatively small and thereby restricted cross-section. With this arrangement, but a small amount of oil will be forced from the inner into the outer receptacle during circuit interruption for the reason that the period of duration of elevated pressure in the inner receptacle during circuit interruption is relatively short. There may be a relatively long period of time between two successive operations of the switch to interrupt the circuit and this time usually is ample for the flow of oil through said small passages from the outer into the inner receptacle to restore the normal oil level in said inner receptacle. The switch may also be so arranged as to permit a plurality of rapidly repeated operations without detrimental reduction of oil in said inner receptacle and loss of oil into the atmosphere from said outer receptacle by providing the inner oil receptacle with sufficient oil capacity.

The term "outer" and "inner" receptacle is herein intended to include any construction wherein two oil containing compartments are provided, in one of which the switch members are adapted to be contained and which is arranged to vent into the other compartment.

It is to be noted that the construction and arrangement of the switch frame and oil receptacles provides oil separator apparatus wherein the oil-laden gas is given centrifugal motion as it passes upwardly about the lower edge of the flange 19, with the result that the oil is projected out of the gas stream into the relatively dead gas space above the oil level in the outer oil receptacle.

10 It is obvious that the invention may be incorporated in other modified structures without departing from the spirit thereof.

I claim:

1. An electric switch having an oil receptacle freely vented above the oil level therein, and self-contained means to catch oil expelled from the receptacle through the vent and subsequently return the oil to the receptacle beneath the oil level therein.

20 2. An electric switch having a switch frame, inner and outer oil receptacles disposed beneath said frame and both adapted normally to contain oil to the same level, said inner receptacle arranged to vent into said outer receptacle above the oil level, and means to return to the inner receptacle oil expelled from said inner to said outer receptacle through said vent.

30 3. An electric switch having a switch frame, inner and outer oil receptacles disposed beneath said frame and both adapted normally to contain oil to the same level, said inner receptacle arranged to vent into said outer receptacle above the oil level, and an oil passage connecting said outer and inner receptacles adapted to return to the inner receptacle oil expelled from said inner into said outer receptacle through said vent.

40 4. An electric switch having a switch frame, inner and outer oil receptacles disposed beneath said frame and both adapted normally to contain oil to the same level, said inner receptacle arranged to vent into said outer receptacle, an oil passage connecting said outer and inner receptacles adapted to return to the inner receptacle oil expelled from said inner into said outer receptacle through said vent and a valve arranged to govern the direction of flow of oil in said passage.

50 5. An electric switch having inner and outer oil receptacles both adapted normally to contain oil to the same level and a free vent passage connecting said two receptacles above the oil level therein, said switch adapted to expel oil from said inner receptacle through said vent passage into said outer receptacle and raise the oil level therein, and means to equalize the oil level in said receptacles.

60 6. An electric switch having inner and outer oil receptacles both adapted normally to contain oil to the same level and a free vent passage connecting said two receptacles

above the oil level therein, said switch adapted to expel oil from said inner receptacle through said vent passage into said outer receptacle and raise the oil level therein, and means to equalize the oil level in said receptacles comprising an oil passage in communication with the oil spaces of said receptacles below the oil level therein.

7. An electric switch having inner and outer oil receptacles both adapted normally to contain oil to the same level and a vent passage connecting said two receptacles above the oil therein, said switch adapted to expel oil from said inner receptacle through said vent passage into said outer receptacle and raise the oil level therein, and means to equalize the oil level in said receptacles comprising a valve-controlled oil passage in communication with the oil spaces of said receptacles below the oil level therein.

8. An electric switch having a switch frame, inner and outer oil receptacles disposed below said frame both adapted normally to contain oil to the same level, a vent passage connecting said receptacles above the surface of the oil therein, an oil passage connecting the oil spaces of said receptacle below the surface of the oil therein, and a check valve arranged to close said passage against flow of oil from said inner into said outer receptacle and to open said passage for flow of oil from said outer into said inner receptacle.

9. An electric switch having a switch frame, inner and outer oil receptacles disposed beneath said frame both adapted normally to contain oil to the same level, a free vent passage connecting said receptacles above the oil therein, and means actuated by a difference in oil level in said receptacles to neutralize the difference in oil level in said receptacles.

10. An electric switch having a switch frame, inner and outer oil receptacles disposed beneath said frame both adapted normally to contain oil to the same level, a vent passage connecting said receptacle above the oil therein, and means comprising a valve actuated by an elevated oil level in said outer receptacle to admit oil from said inner receptacle.

11. An electric switch comprising a switch frame, an oil receptacle having outer and inner oil compartments disposed below said frame, said inner compartment having a vent into said outer compartment, said receptacle having an oil passage in the lower portion of the wall of the inner compartment arranged to provide oil communication between the compartments and a check valve in said inner compartment arranged to close said passage against flow of oil from said inner into said outer compartment.

12. An electric switch having inner and outer oil receptacles with peripherally spaced side walls, a switch frame comprising a cover for said receptacles having an inner depending apron peripherally enclosing and closely spaced from the side wall of said inner receptacle whereby to provide a vent passage from said inner receptacle over and down the side wall thereof into said outer receptacle and an outer depending apron peripherally enclosing and closely spaced from the side wall of said outer receptacle whereby to provide a vent passage from said outer receptacle over and down the side wall thereof into the atmosphere.
13. An electric switch having inner and outer oil receptacles with peripherally spaced side walls, a switch frame comprising a cover for said receptacles having an inner depending apron peripherally enclosing and closely spaced from the side wall of said inner receptacle whereby to provide a vent passage from said inner receptacle over and down the side wall thereof into said outer receptacle and an outer depending apron peripherally enclosing and closely spaced from the side wall of said outer receptacle whereby to provide a vent passage from said outer receptacle over and down the side wall thereof into the atmosphere, the lower portion of the side wall of said inner receptacle having an opening therein communicating with the oil space in said outer receptacle, and a check valve in said inner receptacle arranged to cover said opening.
14. An attachment for an electric switch comprising outer and inner oil receptacles, the lower portion of the side wall of said inner receptacle having a uni-laterally conducting oil passage therethrough arranged to establish communication with the oil spaces in said receptacles.
15. An attachment for an electric switch comprising outer and inner oil receptacles, the lower portion of the side wall of said inner receptacle having an oil passage therethrough arranged to establish communication with the oil spaces in said receptacles and a check valve in said inner receptacle arranged to cover said opening and open toward the interior of said inner receptacle.
16. An electric switch including a casing having two compartments adapted to contain oil, a free gas vent connecting said compartments above the oil level, stationary and movable switch members contained in one of said compartments, and a restricted oil passage arranged to establish communication between said compartments below the oil level therein.
17. An electric switch including a casing having two compartments adapted to contain oil, and stationary and movable switch members contained in one of said compartments, said casing having a uni-directionally re-
- stricted oil passage arranged to establish communication between said compartments below the oil level therein.
18. An electric switch including a casing having two compartments adapted to contain oil, and a vent connecting said compartments above the oil level, stationary and movable switch members contained in one of said compartments, and an oil passage connecting said compartments below the oil level therein arranged to establish oil equilibrium in said compartments and restrict the flow of oil from said switch member containing compartment into said other compartment under circuit-interrupting conditions.
19. An electric switch having the combination of open top and closed bottom inner and outer receptacles both adapted to contain oil normally to the same level and a free vent passage connecting said two receptacles above the oil level therein, said switch adapted to expel oil from said inner receptacle through said vent passage into said outer receptacle and raise the oil level therein, relatively movable switch members depending downward into the oil in said inner receptacle, and means to equalize the oil level in said receptacles comprising an oil passage in communication with the oil spaces of said receptacles below the oil level therein.
20. An oil switch having an oil receptacle including an oil space and a gas space, a vent to the atmosphere extended from the gas space, and a separator device in said vent and including a second oil receptacle surrounding said vent, said device arranged to separate oil from the gas stream passing through it and deposit the separated oil in said second receptacle, said second receptacle having means independent of said vent to return the separated oil to the oil receptacle below the oil level therein.
21. An oil receptacle for an electric switch constructed and arranged to provide an oil-containing compartment and an oil-catching compartment both arranged for intercommunication at the upper portions thereof, said oil-catching compartment having a bottom sealed against passage of gas but open for passage of oil therethrough into said oil-containing compartment.
22. An oil receptacle for an electric switch constructed and arranged to provide an oil-containing compartment and an oil-catching compartment both arranged for intercommunication at the upper portions thereof, said oil catching compartment having a bottom sealed against passage of gas but open for passage of oil therethrough into said oil-containing compartment, and a single cover for both compartments.
23. An electric switch having two com-

parts, one of said compartments arranged to contain oil and the switch members and vent into the other compartment above the oil level, said last compartment 5 arranged to vent into the atmosphere, and means to maintain approximately the same oil level in both compartments.

24. An electric switch having two compartments, one of said compartments arranged to contain oil and the switch members and vent into the other compartment, said last compartment arranged to vent into the atmosphere, means arranged to maintain approximately the same oil 15 level in both compartments, a cover for both compartments, and means admitting of a relative movement between said cover and compartments due to gaseous pressure within the switch.

25. An electric switch comprising a casing having an oil receptacle and a cover therefor, and means contained within the casing and below the cover arranged to provide an oil catching compartment having 25 a passage at the top thereof in communication with the receptacle above the oil therein, and deflecting means arranged in the path of the gas stream through said passage and a passage at the bottom thereof 30 arranged to provide oil communication with said oil receptacle below the oil level therein.

26. An electric switch comprising a casing having an oil receptacle and a cover therefor, and means contained within the 35 casing and below the cover arranged to provide an oil-catching compartment having a passage at the top thereof in communication with the receptacle above the oil level therein, and a flange carried by the cover 40 below the top thereof arranged to deflect

downwardly into said compartment gas passing through said passage, and means independent of said passage to return oil from said oil-catching compartment into the oil receptacle.

45

27. An electric switch comprising a casing including an oil receptacle and a cover therefor, means to provide a compartment under the cover, means to provide a gas entrance and a gas exit at the top of the 50 compartment, means to direct downwardly toward the bottom of the compartment gas passing through said gas entrance, and means to return oil from said compartment into the oil receptacle.

28. An electric switch having an oil receptacle constructed and arranged to provide an oil-catching compartment, said compartment having an open top, a cover for 55 said receptacle and compartment, a plate spaced from the side walls of and extended downwardly into the top of said compartment, and means to return oil from said oil-catching compartment into said oil receptacle.

65

29. An electric switch having an oil receptacle constructed and arranged to provide an oil-catching compartment in the upper portion thereof, said compartment having an open top, a cover for said receptacle and compartment having a flange 70 extended downwardly over and spaced from the inner wall of and into the top of said compartment, means to conduct oil from said oil-catching compartment to said oil 75 receptacle, and means yieldingly to support the cover in such relation.

In testimony whereof I have signed my name to this specification.

GEORGE A. BURNHAM.
